UNITED STATES PATENT OFFICE.

WILLIAM B. GAYLORD, OF GENEVA, NEW YORK.

RAZOR HANDLE.

1,403,074.

Specification of Letters Patent. Patented Jan. 10, 1922.

Application filed November 27, 1918. Serial No. 264,384.

To all whom it may concern:

Be it known that I, WILLIAM B. GAYLORD, a citizen of the United States, residing at Geneva, in the county of Ontario and State 5 of New York, have invented certain new and useful Improvements in Razor Handles, of which the following is a specification.

This invention relates to the making of metal tools, and more especially to blanks 10 and processes as relating to cutlery; and the object of the same is to produce a metal razor handle.

An important feature of this invention is the matter of economy. I find a metal handle made of one piece is cheaper than any 15 other kind of handle.

Another object of my invention is to do away with parts as far as possible, the invention consisting only of the handle and 20 the pivot between it and the blade.

Other objects will appear in the following specification and claim.

Referring to the drawings:

Figure 1 is a side elevation of a razor embodying my improved handle.

Figure 2 is a central longitudinal section through the handle alone.

Figure 3 is an edge view of the handle alone.

Figure 4 is a cross section on the line 4—4 of Fig. 3.

The razor in the present case comprises the blade B and the shank S.

The handle is made of one piece of metal, 35 preferably aluminum. It is formed with two sides 1 and 2, integrally connected by an end piece 3 at one end and spaced sufficiently from each other to leave a slot 4 between the sides, the slot being preferably a little narrower than the back of the blade B so that 40 when the latter is folded into the slot, it cannot pass through between the sides of the handle and in fact its cutting edge will be protected by the handle as usual. On the 45 inner faces of the sides at the opposite end from their integral connection, are formed bosses 5 and 6 stamped or otherwise made integral with the sides themselves, so that there is provided spaces on the inside of the

metal thus forced inwardly in forming the 50 spacer and leaving a countersink for the rivet head making the head coplanar with the outside thus preventing the head from protruding. These do away with the necessity for washers. Through holes 7 in these 55 bosses is passed a pivot pin 8 which is preferably upset or otherwise riveted at its outer ends so it cannot fall out. The pin passes through the shaft S of the blade as usual.

A razor handle of this type is extremely 60 easy to make and reliable in use. If of aluminum as I prefer, it is not subject to moisture or rust, and is light and attractive and will outlast several blades.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by 75 Letters Patent is:—

A razor handle formed of metal and comprising a pair of sides having a solid thickened portion at one end of the handle for firmly connecting the sides together, each 80 side having an inwardly stamped thickened boss upon its inner side and a countersink upon its outer side extending into said thickened portion, said bosses being in alignment with each other, a blade having a shank 85 extending between said bosses and a pin passing through said holes and bosses and said shank for pivotally supporting the blade upon the handle and being coplanar with the outer surface of said handle, the 90 ends of said pin being riveted to hold the same against displacement.

In testimony whereof I affix my signature in presence of two witnesses.

WILLIAM B. GAYLORD.
